DOUBLE GLAZED WINDOW

John H. Fox, Pittsburgh, Pa., assignor to Pittsburgh Plate Glass Company, a corporation of Pennsylvania

Application December 13, 1935, Serial No. 54,273

9 Claims. (Cl. 20—56.5)

The invention relates to a double glazed window construction and particularly to means which may be employed for dehydrating the air or other gas between the glass sheets and for maintaining a condition of dehydration, so that condensation on the inner faces of the sheets is prevented. The invention has for its principal objects, the provision of improved means which may be applied to the frame in which the glass sheets are mounted, which permits of the ready dehydration of the gas between the sheets without removing the double glazed unit from its mounting in a sash or in a car wall, and the provision of a device of very compact character which carries a dehydrating agent (in communication with the space between the glass sheet) so arranged that a ready replacement of the agent can be effected when the agent has lost its drying effect without permitting any inflow of dust-laden air during the replacement step. Certain embodiments of the invention are illustrated in the accompanying drawings, wherein:

Figure 1 is a front elevation of one of the improved units. Fig. 2 is a section on the line II—II of Fig. 1, such figure including in addition the car framing in which the unit is mounted. Fig. 3 is a section on the line III—III of Fig. 1 and also includes a showing of the car framing. Fig. 4 is a section on the line IV—IV of Fig. 3. Fig. 5 is a section on an enlarged scale through the plug employed in dehydrating the unit. Fig. 6 is an end view of the plug. Fig. 7 is a section through a tool used in connection with the dehydrating operation. And Fig. 8 is a section similar to Fig. 4 through a modification.

The glazing unit comprises the usual glass sheets 1 and 2 (Fig. 2) with the interposed spacer 3 of rubber and a U-shaped frame of the type shown in the application of John H. Fox and Charles E. Stroud, Serial No. 37,036, filed August 20, 1935. This frame consists of the two sections 4 and 5 having the hook interlock 7 and the wedge 8 for holding the parts in assembled relation. The composite frame is mounted in a U-shaped packing 9 carried by the car framing, which in this instance, is shown as made up of the members 10 and 11.

Mounted on a corner of the unit and secured in place by the screws 12 is a casing 13 provided with a transversely extending cavity 14 threaded interiorly to receive the casing 15, which carries a suitable dehydrating agent 16, such as aluminum oxide. When this casing is screwed into place, it is packed by means of the gasket 17, the inner end of the casing being closed by a

removable perforated lid 18. Lying just inside of this lid is a screening or filter member 19 preferably of felt or similar material. The inner portion of the cavity 14 has in communication therewith a pair of passages 20 and 21 (Fig. 4) having the enlargements 22 and 23 at their ends. Gaskets 24 of rubber are provided in these ends and receive the outer tapered ends of the tubes 25, 25. These tubes 25 extend through the frame of the unit and through the rubber spacer 3, as indicated in Fig. 4, thus providing communication between the cavity 14 and the insulating space 26 between the glass sheets, so that the space between the glass sheets is constantly in communication with the interior of the casing 15, which carries the dehydrating material. As a result, the humidity of the gas in the space between the glass sheets is maintained at a relatively low point as long as the humidifying agent 16 is active. The gas in the space between the glass sheets is, therefore, maintained relatively dry for a long period.

When the dehydrating material loses its drying capacity and any cloudiness due to condensation appears on the inner faces of the glass sheets, the casing 15 may be removed and a new one substituted containing a fresh charge of dehydrating material. This renewal is readily accomplished by reason of the location of the casing 15, as indicated in Fig. 3, such casing projecting through the plate 11, which constitutes the inner member of the car frame. The making of the tubes 25, 25 separate from the casing 13 instead of integral therewith is advantageous, as it is much easier to position the tubes when they are separate from the casing, and then subsequently fit the casing thereover, than it is to fit a casing to the frame of the unit with the tubes attached thereto.

Fig. 5 illustrates the device which is preferably employed in dehydrating the unit in the first instance, or in dehydrating it after one of the casings 15 has been removed and before the application of another one. This device includes a sleeve 27 which is provided with the gasket 28 and threaded at its inner end so that it screws into the casing 13. Fitting slidably in the sleeve is a tube 29 provided with the passages 30 and 31, the passage 31 at its outer end opening to the atmosphere, while the passage 30 has at its outer end the threaded portion 32 adapted to be connected to a supply tube, such supply tube in turn leading to a container in which is carried a body of dehydrated air or inert gas, such as nitrogen. Secured to the inner end of the

tube 28 is a head 33 of soft rubber, such head being held in place by means of a pair of screws 34. A pair of copper tubes 35 and 36 lead from the inner ends of the passages 28 and 31 to ports at the surface of the plug. When the tube 28 is properly positioned in the cavity 14 of the casing 13, the ends of the tubes 35 and 36 register with the inner ends of the passages 28 and 21 (Fig. 4) so that when dehydrated air is forced through the passage 36, it flows through the passage 28 and tube 25 to the space between the glass sheets, and after circulating through such space, is exhausted through the other tube 25 and passage 21 to the passage 31 of the tube 28. After this circulation has been continued for a sufficient period, any moisture-laden gas between the glass sheets is removed and a dry gas substituted therefor.

After this operation has been completed, the plug is removed and one of the casings 15 is substituted, thus acting as a closure for the cavity 14. The end of the sleeve 27 surrounding the tube 14 is slotted, as indicated at 37 (Fig. 5) and threaded. This threaded end carries a clamping sleeve 38 which locks the sleeve to the tube when it is screwed inward over the tapering portion of the sleeve. This arrangement permits the tube 29 to be rotated in the sleeve 27 to bring the ends of the tubes 35 and 36 into registration with the ends of the passages 28 and 21 and insures a tight joint between the sleeve and the tube when the clamping sleeve 38 is screwed inward. This dehydrating connection can be used to advantage even when the casing 15 carrying dehydrating material is not employed, in which case the cavity 14 may be closed by a screw cap which does not employ a cavity for dehydrating material.

Fig. 7 illustrates a tool which may be employed to advantage to prevent the entrance of any dust-laden air to the window space when it becomes necessary to change the container 15. When this change is accomplished, the space between the glass sheets may be below atmospheric pressure, so that on unscrewing the casing 15, there will be a flow of air to the space between the glass sheet. In case this occurs in the presence of moisture-laden or dust-laden air, the inner surfaces of the glass sheets may be covered with condensation and dust if this is not guarded against. To avoid this difficulty, the device of Fig. 7 is employed, comprising a casing 39 provided with a gasket 40 which may be pressed up against the end of the casing 15. The casing 39 is provided with a packing gland 41, through which extends the shaft 42 provided with a gimlet end 43 and having a handle 44. The end of the casing 15 is relatively thin, so that it may be readily punctured on pressing the shaft 42 inward and turning it. The cavity 45 in which the gimlet end 43 is located has connected thereto a tube 46 provided with a valve 47 and a flexible pipe 48 leading to a container, such as a rubber bag carrying a dry gas, either air or nitrogen. When the end of the casing 15 is punctured, any inflow of gas to the space between the glass sheets is free of dust and dry in character, so that no injury results, such as would occur if the air were moist and dust-laden. By the use of this device a partial drying of the gas between the glass sheets is accomplished, so that the subsequent drying operation requires less time. The use of the tool, as above described, is followed by the dehydrating operation employing the plug shown in Fig. 5, after which

a new casing similar to the casing 15 and carrying a dehydrating agent is screwed into position.

The device as described and illustrated is applicable not only to car windows, but also to the windows of buildings of the double glazed type and permits of the ready dehydration of the units without removing them from position, thus reducing the dehydrating cost to a minimum. The containers for the dehydrating material are relatively inconspicuous and may be removed and replaced at small expense. By their use the period between dehydrating operations is greatly lengthened and in many cases the removal and replacement of the units at regular intervals is all that is necessary to keep the windows from clouding and to remove any cloudiness when such cloudiness appears.

Fig. 8 illustrates a modification which differs from that of Fig. 4 in that the casing 13a is applied to one of the flat sides of the unit adjacent the corner. It is preferably applied adjacent the corner, as it is found that in dehydrating a much better circulation occurs where the two adjacent tubes 25, 25 are located near the corner of the unit. Under these conditions, the incoming gas from the tube next to the vertical side of the unit flows down along such side, circulates around the periphery of the unit and makes its exit through the other tube. A unit may be dehydrated with this arrangement much more rapidly than if the tubes are placed at opposite corners of the unit or at opposite sides thereof, so that the arrangement involving the use of the two tubes adjacent each other at one corner of the unit is advantageous, not only because of the greater compactness and lower cost, but also because of the better circulation which is secured, this materially shortening the time for dehydrating the unit. This circulation is further improved by either cooling the incoming gas by circulating it through a cooler before it reaches the casing 13, or by applying heat to the vertical edge of the unit opposite to the vertical edge at which the gas is introduced. The improved circulation produced by this corner arrangement involving two tubes has been demonstrated by comparative tests of the present arrangement, as compared with one in which the tubes are located at opposite corners of the unit.

What I claim is:

1. In combination in a double glazed window construction, a pair of opposing glass sheets spaced apart, a spacer between the sheets at their margins, which acts as a seal, a frame of metal of U cross section around the edges of the sheets, a pair of tubes adjacent each other extending through the base portion of the frame and the spacer, a casing mounted on the base portion of the frame over the outer ends of said tubes and provided with a pair of passages in communication with said tubes and with a cavity of circular cross section extending transversely of the casing and glass sheets and communicating with said passages, a plug provided with a pair of passages extending longitudinally thereof adapted to fit removably into the cavity with the inner ends of the passages in registration with the ends of the first pair of passages, one of said passages in the plug communicating at its outer end with the atmosphere and the other passage having at its outer end means for connecting it with a conduit for supplying dehydrated gas, and means for closing the outer end of the cavity when the plug is removed therefrom.

2. In combination in a double glazed window

construction, a pair of opposing glass sheets spaced apart, a spacer between the sheets at their margins which acts as a seal, a frame of metal of U cross section around the edges of the sheets, 5 a pair of tubes adjacent each other extending through the base portion of the frame and the spacer, a casing mounted on the base portion of the frame over the outer ends of said tubes and provided with a pair of passages in communication 10 with said tubes and with a cavity of circular cross section extending transversely of the casing and glass sheets and communicating with said passages, a plug provided with a pair of passages extending longitudinally thereof adapted to fit 15 removably into the cavity with the inner ends of the passages in registration with the ends of the first pair of passages, one of said passages in the plug communicating at its outer end with the atmosphere and the other passage having at its 20 outer end means for connecting it with a conduit for supplying dehydrated gas, and means for closing the outer end of the cavity when the plug is removed therefrom, said last means consisting of a container opening into the cavity and provided 25 with a body of dehydrating material.

3. In combination in a double glazed window construction, a pair of opposing glass sheets spaced apart, a spacer between the sheets at their margins which acts as a seal, a frame of metal of 30 U cross section around the edges of the sheets, a pair of tubes adjacent each other extending through the base portion of the frame and the spacer, a casing mounted on the base portion of the frame over the outer ends of said tubes and provided with a pair of passages in communication 35 with said tubes and with a cavity of circular cross section extending transversely of the casing and glass sheets and communicating with said passages, a plug provided with a pair of passages extending longitudinally thereof adapted to fit 40 removably into the cavity with the inner ends of the passages in registration with the ends of the first pair of passages, one of said passages in the plug communicating at its outer end with the atmosphere and the other passage having at its 45 outer end means for connecting it with a conduit for supplying dehydrated gas, a sleeve on the plug threaded into the wall of the cavity for securing the plug in the cavity, means carried by the sleeve for locking the plug against relative 50 movement therein, and means for closing the outer end of the cavity when the plug and sleeve are removed therefrom.

4. In combination with a double glazed window consisting of a pair of glass sheets with a spacer between the sheets at their edge which acts as a seal, means for securing a circulation of dehydrated gas between the sheets comprising a pair of tubes extending through the seal at one 55 of the upper corners of the window and adjacent each other, one of which acts as an inlet to the space between the sheets and the other of which acts as an outlet and a connection for the outer end of the inlet tube whereby a dehydrated gas may be supplied to said space.

5. In combination in a double glazed window construction, a pair of opposing glass sheets spaced apart, a spacer between the sheets at their margins which acts as a seal, a frame of metal of 60 U cross section around the edges of the sheets, a pair of tubes adjacent each other extending through the base portion of the frame and the spacer, a casing mounted on the base portion of the frame over the outer ends of said tubes and provided with a pair of passages in communica-

tion with said tubes and with a cavity of circular cross section extending transversely of the casing and glass sheets and communicating with said passages, a plug provided with a pair of passages extending longitudinally thereof adapted to fit 5 removably into the cavity with the inner ends of the passages in registration with the ends of the first pair of passages, one of said passages in the plug communicating at its outer end with the atmosphere and the other passage having at its outer end means for connecting it with a conduit for supplying dehydrated gas, means for closing the outer end of the cavity when the plug is removed consisting of a cylindrical casing containing a dehydrating material and opening 10 to the interior of the casing, said container having a perforable outer end, and means for perforating such outer end of the container while sealing the perforation from the atmosphere, comprising a cover member adapted to fit over 15 and make a seal with the container and provided with a connection leading to a supply of dehydrated gas, and a perforating tool slidably mounted in the cover member and operable from the exterior thereof to perforate the end of the 20 container.

6. In combination in a double glazed window construction, a pair of opposing glass sheets spaced apart, a spacer between the sheets at their margins, which act as a seal, a frame of metal of 30 U cross section around the edges of the sheets, a pair of tubes adjacent each other extending through the base portion of the frame and the spacer, a casing mounted on the base portion of the frame over the outer ends of said tubes and provided with a pair of passages in communication 35 with said tubes and with a cavity of circular cross section extending transversely of the casing and glass sheets and communicating with said passages, and means for closing the outer end 40 of the cavity comprising a detachable container communicating with the cavity and carrying a body of dehydrating material.

7. In combination in a double glazed window construction, a pair of opposing glass sheets spaced apart, a spacer between the sheets at their margins, which act as a seal, a frame of metal of U cross section around the edges of the sheets, a pair of tubes adjacent each other extending through the base portion of the frame and the spacer, a casing mounted on the base portion of the frame over the outer ends of said tubes and provided with a pair of passages in communication with said tubes and with a cavity of circular cross section extending transversely 55 of the casing and glass sheets and communicating with said passages, and means for closing the outer end of the cavity comprising a detachable container carrying a body of dehydrating material and having a removable perforated lid at 60 its inner end.

8. In combination in a double glazed window construction, a pair of opposing glass sheets spaced apart, a spacer between the sheets at their margins, which act as a seal, a frame of metal of U cross section around the edges of the sheets, a pair of tubes adjacent each other extending through the base portion of the frame and the spacer, a casing mounted on the base portion of the frame over the outer ends of 70 said tubes and provided with a pair of passages in communication with said tubes and with a cavity of circular cross section extending transversely of the casing and glass sheets and communicating with said passages, and means for 75

closing the outer end of the cavity comprising a tubular container threaded into the cavity and communicating therewith at its inner end and provided with a body of dehydrating material.

5 9. In combination in a double glazed window construction, a pair of opposing glass sheets spaced apart, a spacer between the sheets at their margins, which act as a seal, a frame of metal of U cross section around the edges of
10 the sheets, a casing mounted on the base portion of the frame and having mounted on its inner

side a pair of tubes which extend through the base portion of the frame and the spacer, said casing also being provided with a transverse cavity having communications leading to the inner ends of the tubes, a plug adapted to fit into the cavity and provided with a pair of passages adapted to communicate with said tubes for dehydrating purposes, and means for closing the outer end of the cavity when the plug is removed.

10

JOHN H. FOX.
